COMBINED WATER CLOSET AND FLUSH TANK

Frank E. Cherry, Agate, Nebr.

Application March 29, 1956, Serial No. 40,828

Term of patent 14 years

(Cl. D4—5)

*Fig. 1.**Fig. 2.**Fig. 3.*

Figure 1 is a perspective view of a combined water closet and flush tank, with the lid and seat portions in closed position, showing my new design;

Figure 2 is a front elevational view thereof as seen in Figure 1; and

Figure 3 is a perspective view thereof with the lid and seat portions in an open position.

I claim:

The ornamental design for a combined water closet and flush tank, substantially as shown.
